(57) **CLAIM**

The ornamental design for display panel portion or screen portion with transitional indicator of the operation of a computer-programmed device, as shown and described.

DESCRIPTION

FIG. 1 is a front view of the first image in the sequence for a transitional user interface for a portion of a display screen showing the new design;

FIG. 2 is a front view of the second image thereof; and,
FIG. 3 is a front view of the third image thereof.

The appearance of the transitional image sequentially transitions between the images shown in FIGS. 1-3. The process or period in which one image transitions to another forms no part of the claimed design. The evenly-spaced broken lines illustrate unclaimed portions of the transitional indicator of the operation of a computer-programmed device and form no part of the claimed design. The unevenly-spaced broken line showing of the portion of the unclaimed display panel or screen is included for the purpose of illustrating unclaimed environment and forms no part of the claimed design.
